ARTICLE-HANDLING TOOL

William H. Harstick, Oak Park, Ill., assignor to
International Harvester Company, a corpora-
tion of New Jersey

Application December 28, 1946, Serial No. 719,039

3 Claims. (Cl. 294—93)

1

This invention relates to an article-handling tool. More specifically, it relates to a device particularly adapted to remove a stack of disks from the bowl of a cream separator for cleaning. In centrifugal cream separators the separating bowl contains a stack of super-imposed conical disks which are supported in a certain order or arrangement. These disks must frequently be removed from the bowl for washing and it is essential that the order of arrangement of the disks be preserved during washing.

The preliminary object of the invention is to provide an improved device for removing and supporting for cleaning a plurality of stacked apertured elements such as the disks of a centrifugal separator.

A more specific object is to provide such an article-handling device which engages the elements to be carried at a plurality of locations and which can be readily actuated to engage the disks by a finger of the operator while holding the supporting structure of the device in one hand.

The above objects, and others which will be apparent from the detailed description to follow, are obtained by a construction such as shown in the drawings, in which

Figure 1 is a view in elevation of an article-handling tool with portions broken away in section to better show the mounting of the supporting rods and the means by which said rods engage the stack of disks;

Figure 2 is a plan view of the structure shown in Figure 1;

Figure 3 is an enlarged plan view of a portion of Figure 2 broken away in section to show in dotted lines the two positions of the actuating mechanism for oscillating the article-carrying rods;

Figure 4 is a vertical section taken on the line 4—4 of Figure 3;

Figure 5 is a bottom view of a portion of the disk structure of Figure 1 showing also the lower end of one of the disk-supporting rods.

Figure 1 shows a cream separator bowl base 10 on which a stack of separator disks 11 is supported in a conventional manner. It is to be understood that the base 10 is suitably carried by a conventional bowl structure adapted to be mounted for high-speed operation in a centrifugal separator. The disks 11 are provided with a plurality of circular openings 12 which are arranged in axial alignment when the disks 11 are stacked in their operating position. The base 10, as shown both in Figures 1 and 12, is provided with an elongated opening 13 in axial alignment

2

with each series of the openings 12. A plurality of rods 14 are provided with upturned extensions or feet 15 which are adapted to pass through the openings 12 and the openings 13 and to thereafter be returned to the dotted-line position of Figures 1 and 5 to engage the lower surface of the base 10. Figure 5 indicates in dotted lines the position of the extensions 15 when they are being inserted through the openings 13. Each of the rods 14 is provided with a flange or enlargement 16 spaced from the extension 15 to engage the upper surface of the base 10 adjacent the opening 13 whereby said base is held against substantial movement adjacent the ends of the rods 14 while the disks 11 are free to move along the rods and to thereby be separated for effective cleaning.

The rods 14 are rotatably supported by a structure which will now be described. A pair of spaced plates 17 and 18, generally triangular in shape, are provided with central openings 19 and 20 through which the reduced end portions 21 and 22 of a center post 23 extend. As best shown in Figure 4, the reduced end portion 21 forms a shoulder 24 against which the upper plate 17 abuts. The reduced end portion 21 is flared over the upper surface of the plate to rigidly secure said plate in position on the post. To securely hold said plate against rotation the post 23 is formed with a keyway into which an integral extension 26 on the upper plate 17 extends. It is to be understood that the lower plate 18 is secured in a similar manner to the post 23.

The upper plate 17 is provided with a down-turned stiffening flange 26 and the lower plate 18 is provided with a similar up-turned stiffening flange.

The plates 17 and 18 are provided at their apices with aligned openings 28 through which the rods 14 rotatably extend. Each rod is held in place against axial movement by a winglike member 29 having spaced side portions 30 and 31 which are curved around opposite sides of the rods to which it is attached and secured thereto by spot welds such as indicated at 33 in Figure 1. The spaced side portions 30 and 31 are integrally joined by a U-shaped portion 34, the sides of which are closely spaced to frictionally receive downwardly turned projections 35 integrally extending from the periphery of a generally circular actuating member 36.

As best shown in Figure 1, the winglike members 29 are provided with notched end portions 37, said notches, as indicated by the lines in Figure 3, extending towards the rods 14 a sufficient

distance to allow swinging of the rods with the members 29 without engaging the periphery of the actuating member 36. Said notches provide a space between the end portions of the members 29 and the upper plate 17 in which the actuating member 36 is seated to hold it against movement in an axial direction. As best shown in Figure 4, the actuating member 36 is provided with a central opening 38 to provide a bearing on the post 23. By means of this construction the actuating member 36 is free to be oscillated from the solid-line position, as shown in Figure 3, to the dotted-line position. An extension 40 from the member 36 provides a lever arm for oscillating the member 36. A down-turned extension 40 on said arm provides means adapted to be engaged by the finger of an operator for oscillating the rods.

In the operation of the device as above described one position of the rods 14 is indicated by solid lines in Figure 3, one of the projections 35 being shown as located in the U-shaped portion 34 of one of the winglike members 29. Preferably, the U-shaped portions are so constructed that there is a frictional engagement of the projection 35 to thereby hold the actuating member 36 against rotation. The other position of the actuating member 36 is indicated in dotted lines in Figure 3 with the winglike member 29 swinging around somewhat over 90° to the other side. In this swinging movement the projection 35, which provides the actuating force, leaves the U-shaped portion 35 and moves between the spaced portions 30 and 31, said portions being spaced apart a sufficient distance to allow room for the projection 35 during the swinging movement. It is to be understood that the member 36 has three projections 35, one of which actuates each of the three winglike members 29 carried by the rods 40.

Although applicant has shown his improved article-handling device as embodied in a particular construction, it is to be understood that he claims as his invention all modifications falling within the scope of the appended claims.

What is claimed is:

1. An article handling tool comprising a supporting structure, a plurality of parallel rods mounted on said supporting structure, a wing-like member having two spaced portions extending axially along and secured to each of said rods adjacent said supporting structure, said members being notched adjacent the supporting structure to provide a narrow space between the members and the structure at that end, an actuating member rotatably mounted between said structure and the notched end portions of said members, said actuating member being formed around its periphery with a plurality of inturned projections, one projection extending between the spaced portions of each of the rod connected members and spaced radially from the rod whereby oscillation of said actuating member simultaneously oscillates all of the rods, said rods being formed at their lower ends with means to engage and hold

a plurality of articles to be carried thereon and handled thereby.

2. An article handling tool comprising a supporting structure including two spaced parallel plates and a central post to which said plates are rigidly attached, said plates being formed with a plurality of circumferentially spaced, aligned openings, rods extending through said openings for rotation therein, a wing-like member having two spaced portions extending axially along and secured to each of said rods between said plates and abutting said plates, an actuating member rotatably mounted on the center post, said actuating member being formed around its periphery with a plurality of inturned projections, one projection extending between the spaced portions of each of the rod connected members and spaced radially from the rod whereby oscillation of said actuating member simultaneously oscillates all of the rods, said actuating member also being provided with an extension projecting beyond the plates whereby an operator may engage said extension to oscillate said rods, said rods being formed at their lower ends with means to engage and hold a plurality of articles to be carried thereon and handled thereby.

3. An article handling tool comprising a supporting structure including two spaced parallel plates and a central post to which said plates are rigidly attached, said plates being formed with a plurality of circumferentially spaced, aligned openings, rods extending through said openings for rotation therein, a wing-like member having two spaced portions extending axially along and secured to each of said rods between said plates and abutting said plates, said members being notched at one of their end portions to provide a narrow space between the members and the plate at that end, an actuating member rotatably mounted on the center post between one of said plates and the notched end portions of said members, said actuating member being formed around its periphery with a plurality of inturned projections, one projection extending between the spaced portions of each of the rod connected members and spaced radially from the rod whereby oscillation of said actuating member simultaneously oscillates all of the rods, said actuating member also being provided with an extension projecting beyond the plates whereby an operator may engage said extension to oscillate said rods, said rods being formed at their lower ends with means to engage and hold a plurality of articles to be carried thereon and handled thereby.
